US0D1096912S

(12) **United States Design Patent** (10) **Patent No.:** **US D1,096,912 S**
Luo (45) **Date of Patent:** **** Oct. 7, 2025**

(54) **STARRY SKY PROJECTOR**

(71) Applicant: **Shenzhen Chuangxin Intelligent Lighting Technology Co., Ltd., Shenzhen (CN)**

(72) Inventor: **Liting Luo, Zhanjiang (CN)**

(73) Assignee: **Shenzhen Chuangxin Intelligent Lighting Technology Co., Ltd., Shenzhen (CN)**

(**) Term: **15 Years**

(21) Appl. No.: **29/994,238**

(22) Filed: **Mar. 19, 2025**

(51) LOC (15) Cl. **16-02**

(52) U.S. Cl.

USPC **D16/230**

(58) **Field of Classification Search**

USPC ..... D16/200-202, 208, 214, 217-218, 219, D16/221, 225, 229, 230; D10/104.1, D10/106.6; D14/125, 128, 129, 131, D14/138 C, 203.1, 209.1, 474; D21/490, D21/514, 515, 516, 584, 611

CPC G03B 21/00; G03B 21/12; G03B 21/14; G03B 21/16; G03B 21/145

(57) **CLAIM**

The ornamental design for a starry sky projector, as shown and described.

DESCRIPTION

FIG. 1 is a top, front, right side perspective view of a starry sky projector, showing my new design;

FIG. 2 is a bottom, front, left side perspective view thereof;

FIG. 3 is a top, rear, left side perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is an enlarged view of the portion 10 in FIG. 1;

FIG. 11 is an enlarged view of the portion 11 in FIG. 2; and,

FIG. 12 is an enlarged view of the portion 12 in FIG. 3.

The evenly dashed broken lines illustrate portions of the starry sky projector and form no part of the claimed design. The dash-dot-dash broken lines define the boundaries of enlarged views and form no part of the claimed design.

1 Claim, 12 Drawing Sheets
